CLAIM

We claim the ornamental design for the hand-held rotary tool, as shown and described.

DESCRIPTION

FIG. 1 is a perspective view of a hand-held rotary tool showing our new design;

FIG. 2 is a top plan view thereof;

FIG. 3 is a bottom plan view thereof;

FIG. 4 is a right-side elevation view thereof;

FIG. 5 is a left side elevation view thereof;

FIG. 6 is a front elevational view thereof; and,

FIG. 7 is rear elevational view thereof.

The broken lines shown in the drawings represent portions of the hand-held rotary tool that form no part of the claimed design.
